UNITED STATES PATENT OFFICE.

WILLIAM H. SNEDEKER, OF NYACK, NEW YORK.

DESIGN FOR A STRAINER MUSTACHE-GUARD FOR DRINKING VESSELS.

SPECIFICATION forming part of Design No. 35,231, dated October 29, 1901.

Application filed September 23, 1901. Serial No. 76,296. Term of patent 14 years.

To all whom it may concern:

Be it known that I, WILLIAM H. SNEDEKER, a citizen of the United States, residing at Nyack, in the county of Rockland and State of New York, have invented and produced a new and original Design for Strainer Mustache-Guards for Drinking Vessels, of which the following is a specification, reference being had to the accompanying drawings, forming part thereof.

Figure 1 is a side view; Fig. 2, a front view, and Fig. 3 a plan view.

As shown in the drawings, my design consists of an inverted semicouical shell-like portion 1, having perforations 2, a flared portion 3, whose lower portion conforms to the curved outline 4 of the part 1 and extends above the latter at an angle thereto, being

provided with the radiating ribs 5 and 6 and having its edge formed into the curve 7, 8, 20 and 9. At the sides of the flared part 3 are depending members 10 and 11, having the rounded portions 12 where they join the same.

Having described my invention, what I claim as new, and desire to secure by Letters 25 Patent, is—

The design for a strainer mustache-guard for drinking vessels as herein shown and described.

In testimony whereof I have signed my 30 name to this specification in the presence of two subscribing witnesses.

WILLIAM H. SNEDEKER.
